UNITED STATES PATENT OFFICE.

JACQUES WORTH, OF PARIS, FRANCE.

DESIGN FOR A FLASK.

Application filed May 12, 1924. Serial No. 9,567. Term of patent 14 years.

To all whom it may concern:

Be it known that I, JACQUES WORTH, a citizen of the Republic of France, residing at Paris, France, have invented a new, original, and ornamental Design for Flasks, of which the following is a specification, reference being had to the accompanying drawing forming part thereof.

In the drawings:

Fig. 1 is a front elevation of the flask;
Fig. 2 is a side elevation of the flask.

I claim:

The ornamental design for a flask, as shown.

In testimony whereof I affix my signature.

JACQUES WORTH.
